T. R. BROWN.
AUTOMATIC SLACK ADJUSTER.
APPLICATION FILED APR. 30, 1919.

1,388,020.

Patented Aug. 16, 1921.

Thomas R. Brown
by *John M. Brady* Atty.

UNITED STATES PATENT OFFICE.

THOMAS R. BROWN, OF PITTSBURGH, PENNSYLVANIA, ASSIGNOR TO AMERICAN BRAKE COMPANY, OF ST. LOUIS, MISSOURI, A CORPORATION OF MISSOURI.

AUTOMATIC SLACK-ADJUSTER.

1,388,020.

Specification of Letters Patent. Patented Aug. 16, 1921.

Application filed April 30, 1919. Serial No. 293,878.

To all whom it may concern:

Be it known that I, THOMAS R. BROWN, a citizen of the United States, residing at Pittsburgh, in the county of Allegheny and 5 State of Pennsylvania, have invented new and useful Improvements in Automatic Slack-Adjusters, of which the following is a specification.

This invention relates to automatic slack adjusters adapted to take up slack due to the 10 wear of the brake shoes on the wheels of a railway vehicle.

The principal object of my invention is to 15 provide an improved slack adjuster of the above character.

In the accompanying drawing, Figure 1 is a central sectional view of a slack adjuster embodying my invention; Fig. 2 a section on the line 2—2 of Fig. 1; Fig. 3 a face view 20 of the manually operated resetting member; Fig. 4 a plan view of a portion of the slack adjuster, showing the means for resetting the parts; and Fig. 5 a central sectional view 25 of a modified construction embodying my invention.

According to my invention, in place of the usual bottom rod, I provide an adjustable bottom rod connecting the usual brake levers 1 and 2 and comprising a casing 3, 30 pivotally connected by arms 4 to the brake lever 2 at a point above that at which the bottom rod is ordinarily connected.

Mounted within the casing 3 is a rod 5, 35 pivotally connected to the lower end of the brake lever 1, and having its outer end carried by a sleeve 6, which is slidably mounted in the casing 3 and is adapted to be engaged either by the end of the brake lever 2, or, as shown in the drawing, by a wear plate 7, 40 secured to said lever.

Within the casing and mounted on the rod 5 are semi-sleeve clutch members 8 and 9 which are held together by a tiltable ring 10.

The clutch member 9 is in engagement 45 with the sleeve 6, while a clearance space is normally provided between the member 8 and said sleeve.

Adjacent to the brake lever 1, the casing 3 contains a pair of semi-sleeve clutch members 11—11, which are maintained in frictional contact with the rod 5 by a tightly wound coil spring 12 and are held against movement relative to the rod in one direction by a collar 13, adapted to engage a flange 50 14 on the semi-sleeve members 11—11.

In order to prevent rotative movement of the semi-sleeve members 8 and 9, the member 8 is provided with a tang 15 adapted to engage between guide members 16—16 on the casing 3.

In operation, if the brakes are applied and there is no excess movement of the brake levers 1 and 2 due to wear of the brake shoes, the arrangement acts as an ordinary bottom rod, without any slack adjusting 65 action taking place.

If there is an excess movement of the brake levers in applying the brakes, however, the angularity of the brake levers 1 and 2 will be increased beyond the normal, and 70 this will cause the brake lever 2 to pull the casing 3 in the direction of said lever and relatively to the rod 5, thereby compressing the spring 17 between the collar 13 and the semi-sleeve members 8 and 9.

During this movement, the member 7 engages the sleeve 6 and the pressure thereby exerted on said sleeve acts on the semi-sleeve member 9, so as to tend to tilt the ring and cause the semi-sleeve members 8 and 9 80 to tightly grip the rod 5. The rod 5 and the sleeve 6 thus act as a fixed bottom rod and constitutes a fulcrum through which excess movement of the brake levers cause the relative movement of the casing 3.

The collar 13 will move away from the semi-sleeve members 11 and the end of the casing 3 will engage said members, and then the further movement of the casing causes the semi-sleeve members 11 to slide forward 90 on the rod 5.

Upon releasing the brakes, the release movement causes the lower end of lever 2 to tend to move away from the sleeve 6, and the sleeve 6 being thus free to move to 95 the right, the lower grip member 9 is no longer held against movement by the sleeve 6, so that the spring 17 acting with equal pressure on both grip members 8 and 9 causes a relative movement between said 100 members and thereby a movement of the ring 10 from its tilted gripping position. The grip members then slip forward on the rod 5, causing the sleeve 6 to follow up the end of lever 2; any tending of the rod 105 5 to move forward being prevented by the engagement of the semi-sleeve members 11—11 with the collar 13.

The result is that the effective length of the bottom rod member will be increased to 110

correspond with the wear of the brake shoes, so that upon the next application of the brakes, the slack will have been taken up.

In order to permit the replacement of a worn out brake shoe with a new brake shoe and the resetting of the parts to their initial positions, a hand operated member 30 is provided, which has a ring portion adapted to fit over the sleeve 6 and a notch 18 adapted 10 to engage a spline 19 on the sleeve. The member 30 is held against longitudinal movement with respect to the casing 3, by means of flanges 20 and 21.

The sleeve 6 is provided on its end face 15 with opposite inclined surfaces 22 adapted to engage corresponding inclined surfaces 23 on the semi-sleeve member 8, as shown more clearly in Fig. 4 of the drawing.

When it is desired to reset the parts to their initial positions, the member 30 is 20 manually rotated in either direction from the vertical position so that the surfaces 22 will engage the corresponding one of surface 23 on the member 8 and thereby cause a rearward movement of the semi-sleeve member 8. This tends to loosen the ring 10, by 25 throwing the same to a vertical position, so that the semi-sleeve members 8 and 9 are released from their grip on the rod 5, permitting the same to slip forward until the 30 end again engages the end of the sleeve 6. If the operator should forget to return the member 30 to its normal vertical position, said member will be returned by gravity 35 upon applying the brakes.

A modified construction embodying my invention is shown in Fig. 4 of the drawing, in which the friction clutch comprises a plurality of tilting rings 24, 25, and 26, the 40 ring 24 being engaged by spring 17' and the ring 26 by a bar 27, the outer end of which is adapted to engage the end of the brake lever 2'.

The operation is similar to that of the 45 construction shown in Fig. 1, and in applying the brakes, the movement of the lever 2' causes the casing 3' to be pulled forward, compressing the spring 17'. Excess movement of the brake lever causes the semi-sleeve members 11'-11' to engage the rear 50 end of the casing 3', and then said members slip forward on the rod 5'.

Upon releasing the brakes, the brake lever 2' tends to move away from the bar 27, but 55 the spring 17' then acts to straighten up the rings 24, 25, and 26, since the bar 27 moves forward with the brake lever 2'. The casing 3' consequently is permitted to move relatively to the rod 5, so that the bottom 60 rod member is lengthened and the slack is taken up.

The parts may be reset in the same manner as in the case of the construction shown in Fig. 1, by providing an inclined face 23' 65 adapted to be engaged by a corresponding

inclined face on the member 30', so that the rotation of the member 30' causes the rings 24, 25, and 26 to be shifted to a vertical position, permitting the rod 5' to move forward until the end engages the end of the 70 casing 3'.

Having now described my invention, what I claim as new, and desire to secure by Letters Patent, is:—

1. In an automatic slack adjuster, the combination with brake levers and adjustable members operatively connecting said levers, of friction grippers for engaging one of the adjustable members and a tiltable ring for forcing the grippers into gripping engagement with said member. 75

2. In an automatic slack adjuster, the combination with brake levers and adjustable members operatively connecting said levers, of friction grippers for engaging one of the 80 adjustable members and a tiltable ring adapted to be tilted to force the grippers into gripping engagement with said member upon the application of force to one of the grippers through the other adjustable 85 member.

3. In an automatic slack adjuster, the combination with brake levers, of a rod connected to one lever, a sleeve engaging the other lever, semi-sleeve friction grippers 90 mounted on the rod, and a tiltable ring enclosing said grippers and adapted to be tilted to force the grippers into gripping engagement with said rod. 95

4. In an automatic slack adjuster, the combination with brake levers, of a rod connected to one lever, a clutch device for holding said rod in position, a casing operatively connected to the other brake lever, and a spring operated by said casing for releasing 105 said clutch.

5. In an automatic slack adjuster, the combination with brake levers, of a rod connected to one lever, a clutch device for holding said rod in position, a member operated 100 by the other brake lever for causing said clutch to maintain its holding engagement with the rod, a casing operatively connected to the last mentioned brake lever, and a spring compressed by the movement of the 115 casing for releasing said clutch.

6. In an automatic slack adjuster, the combination with brake levers, of adjustable members operatively connecting said levers, a clutch device for holding one of said members in its adjusted position, and having an inclined face, and a manually operated member having a corresponding inclined face adapted to engage with the inclined face of the clutch device for releasing same. 120

7. In an automatic slack adjuster, the combination with brake levers, of adjustable members operatively connecting said levers, a clutch device for holding one of said members in its adjusted position, and having an 130

inclined face, the other adjustable member having a corresponding inclined face, and a manually operated arm for rotating said adjustable member to thereby cause the engagement of said inclined faces.

8. In an automatic slack adjuster, the combination with brake levers, of a rod connected to one brake lever, a sleeve mounted on said rod and adapted to be engaged by 10 the other brake lever, a clutch device com-

prising one member adapted to be engaged by said sleeve for causing the clutch to act, and another member adapted to be engaged by said sleeve upon rotation for releasing the clutch, and a manually operated member 15 for rotating said sleeve.

In testimony whereof I have hereunto set my hand.

THOMAS R. BROWN.
